UNITED STATES PATENT OFFICE.

JOSEPH HENRY WARWOOD, OF BEAVER FALLS, PENNSYLVANIA.

BRICK KILN FURNACE.

Application filed January 27, 1926, Serial No. 84,207

The present invention relates to improvements in brick kiln furnaces, and has for an object to provide an improved furnace for this purpose in which a clean fire, better draft and an economy of fuel will be secured.

A further object of the invention resides in providing an improved furnace, which will be for all purposes practically smokeless, which will be easy to fire and handle and will be less affected by high winds than the present types of kiln furnaces.

With the foregoing and other objects in view, the invention will be more fully described hereinafter, and will be more particularly pointed out in the claims appended hereto.

In the drawings, wherein like symbols refer to like or corresponding parts throughout the several views,

20 Figure 1 is a front elevation of a kiln furnace constructed according to the present invention.

Figure 2 is a vertical section taken on the line 2—2 in Figure 1.

25 Figure 3 is a horizontal section taken on the line 3—3, also in Figure 1.

Figure 4 is a front perspective view of the draft furnace front frame, and

30 Figure 5 is a rear perspective view of the same.

Referring more particularly to the drawings, 6 designates generally the kiln in which the bricks are placed and 7 indicates a combustion chamber of one of the furnaces, of 35 which there will be several, in accordance with the usual custom distributed about the circular kiln 6.

The furnace grate is represented at 8 and the ash pit at 9. The grate 8 will be a shaking grate whereby it will be easy to maintain a clean fire.

In the front wall 10 of the furnace are the usual sight openings 11, 12 and 13, through which the progress of the action in the furnace may be observed. In accordance with 45 the invention the furnace front wall 10 is provided with a number of circular or arched rows of bricks, three such rows numbered 14, 15 and 16 being illustrated by way 50 of example. Circumscribed by the inner row is a substantially semi-circular space left for the front frame, which is shown more particularly in Figures 4 and 5 and comprises generally the outer and inner circular walls 17 and 18 respectively spaced 55 apart and connected along their outer curved

edges by the front wall 19. These three walls are preferably built into a composite and integral structure, advantageously from sheet metal and the outer curved wall 17 is 60 preferably of less depth than the inner curved wall 18 (see Figure 2). The frame, so built up, is set well back within a pocket provided by the inner brick arch 14 and the inner edges of the curved walls 17 and 18 65 both fit against the outer vertical surface 20 of a depending curved shoulder 21 made as a part of the front furnace wall 10. This shoulder 21 overhangs the fire box and the grate 8 and the lower furnace wall 22 below 70 the metal frame is sloping as to its inner surface, as indicated at 23 outwardly and upwardly from the grate or the fuel bed resting upon the grate. This sloping inner wall 23 intersects the vertical prolongation 75 of the wall 20 and the upper end of the sloping surface 23 is situated well outward with reference to the metal frame. This permits the coal, which is inserted through the opening provided by the inner curved plate 18 80 to be deposited directly beneath the metal frame and the shoulder 21. Air, as herein-after described will thus get at the fresh coal which has just been placed in the furnace and combine with the gases evolved therefrom for the purpose of eliminating smoke.

A door 24 also preferably of metal and of a substantially semi-circular construction is fitted to the opening defined by the inner curved metal wall 18 and this door is removed when the fuel is fed to the furnace.

As shown particularly in Figure 5, the ends of the outer curved wall 17 of the frame are cut away as indicated at 25 and 26 leaving front leg portions 27 and 28 for the frame to rest upon the furnace structure. The inner curved wall 18 is provided with the central cut away portion or slot 29 preferably made through its rear wall, but leaving substantial portions to fit against the 100 surface 20 of the shoulder 21.

The cut away portions 25 and 26 of the outer curved wall 17 register with draft passages 30 and 31 which extend laterally and horizontally in opposite directions from the metal frame and connect with ports 32 and 33 opening out through the front wall 10. These ports are covered by damper frames 34 and 35 in which slide dampers 36 and 37 provided with the handles as 110 shown for adjustment.

In the use of the device the incandescent

mass of coals will rest directly upon the grate bars 8. Above this mass will be a second mass of coals which have been pre-heated, dried out and from which most of the gas is driven off. This secondary mass is thus prepared for combustion in the usual way. The fresh coal thrown in through the furnace front will be received upon this secondary mass directly beneath the metal frame and the shoulder 21 and this fresh coal will immediately begin to gas heavily and ordinarily would cause considerable smoke. However, suitable quantities of oxygen can be supplied to this gas by appropriately adjusting the dampers 36 and 37. The dampers being open air will be admitted to the passages 30 and 31 and through the cut out portions 25 and 26 to the space contained between the inner and outer walls 17 and 18 of the furnace front frame. The air is required to circulate through an angular distance in the space between these curved walls before arriving at the slot 29 at the central part of the inner wall 18. The air is drawn downwardly through this slot 29 directly into the mass of fresh coal and this air is pre-heated in the front frame in passing about for the angular distance referred to. The air being brought in opposite directions to the central slot 29 will cause a diminution in the velocity of the air currents, one air current striking against and substantially destroying the other, whereby the oxygen will be fed quietly down into the fresh coal bed. It will be apparent that the slot 29 through which this air quietly issues is located very close to the mass of fresh coal and the gas will be taken up quietly by the oxygen.

The furnace is a natural draft furnace and requires no mechanical appliances. It is cheap to install and does not require any special brick shapes.

It will be apparent that it is easy to fire and handle and, due to the inlet of air, the combustion is as complete as practicable. The furnace is much cooler to fire and clean than the average kiln furnace; it is practically smokeless, securing a greater percentage of heat units than present furnaces; and on account of its clear fire and excellent combustion qualities it will be found an ideal coal furnace for high grade brick.

On account of the design of its construction it is less affected by high wind than most kiln furnaces and its design is such that it will not easily burn out and will not often require repairing. The use of this furnace should entail a saving of from 16 to 20 percent of fuel.

It is obvious that various changes and modifications may be made in the details

of construction and design of the above specifically described embodiment of this invention without departing from the spirit 65 thereof, such changes and modifications being restricted only by the scope of the following claims.

What is claimed is:—

1. A brick kiln furnace comprising a front 70 wall having a substantially semi-circular opening therein and having lateral damper-controlled passages communicating with opposite sides of the opening at low points thereof, and a substantially semi-circular 75 front frame mounted in said opening and having inner and outer walls for enclosing a preheating chamber for the air, said outer wall having cut away parts at its ends to register with the air passages in said furnace 80 wall, said inner frame wall having a central slot for directing the air downwardly into the combustion chamber of the furnace.

2. A brick kiln furnace comprising a 85 furnace front wall having a substantially semi-circular opening therein, a lateral damper-controlled air passage communicating with opposite end portions of said opening, and a furnace front frame mounted in 90 said opening and composed of inner and outer spaced curved walls and a sloping front curved wall connecting said inner and outer walls along their outer edges, said outer curved wall having cut away end portions to register with the air passages, said 95 inner curved wall having a central slot for placing the interior of the front frame in communication with the combustion chamber of the furnace.

3. A brick kiln furnace comprising a front 100 wall having a substantially semi-circular opening with a shoulder depending for a distance downwardly at the inner end of the opening, the front wall of the furnace below said opening being provided with an inner sloping wall progressing from a point adjacent the fire box upwardly and outwardly and terminating at a point intermediate the inner and outer ends of said opening, a front 110 frame mounted in said opening with its rear ends engaging against said shoulder and with its bottom edges resting adjacent the upper end of said sloping wall, said frame composed of inner and outer spaced curved walls, and a curved connecting wall joining the 115 outer edges of said inner and outer curved walls, said outer wall having cut away end portions with feet adjoining the cut away portions, said cut away portions arranged to receive air, said inner curved wall having a slot at its intermediate portion for receiving air and permitting it to be drawn into the furnace combustion chamber.

JOSEPH HENRY WARWOOD.
